UNITED STATES PATENT OFFICE.

ALEXANDER S. SPIEGEL, OF CHICAGO, ILLINOIS.

COMPOSITION ROOFING.

1,264,343.

Specification of Letters Patent. Patented Apr. 30, 1918.

Application filed June 10, 1913, Serial No. 772,910. Renewed December 6, 1915. Serial No. 65,420.

To all whom it may concern:

Be it known that I, ALEXANDER S. SPIEGEL, citizen of the United States, residing at Chicago, Illinois, have invented certain new and useful Improvements in Composition Roofing, of which the following is a specification.

In an application filed by me on the 19th of November, 1912, #732,328, issued as a patent December 23, 1913, #1,082,364, I have described means for making composition roofing, in which the surface is broken up into designs varying in color, so as to give the appearance of a roof made up of separate tiles, slates, or shingles, and in the present application I am claiming the articles so made.

My present invention consists as a new article of manufacture in a sheet of asphalt roofing material having designs formed upon its surface, the designs being made distinct by colored sand or grit embedded in the asphalt material. In the use of my patented machine impression lines are made in the soft material by the skeleton cylinder in confining a surface for the application of the particular color of grit to be applied at that point, but it will be understood that the designs upon the surface are wholly made by the different colored material used and the design is not dependent upon impressions made by the sharp edges of the confining section, and it frequently happens in practice, that these impression lines are smoothed out by passing the material between rollers. This invention clearly differentiates from roofing in which an ornamental surface is prepared by applying a coating to the completed surface varying in thickness, and also by depressing certain portions of the surface to create designs. I aim to have a roofing material having an unbroken surface of uniform thickness, the designs appearing in different colors and not dependent upon depressed portions to form the design or a variation in thickness wherein a part of the grit is partially embedded and other parts wholly embedded. The sheet may be provided with an uncovered lap at one side, so as to allow for the matching of the patterns or designs.

In the drawing, the figure is a plan view showing a section of one form of roofing material embodying my improvement.

55 In this drawing I utilize any asphalt com-

position roofing made up of the usual material or layers, and I apply in any suitable manner to the surface, preferably while hot and sticky, a sand or grit, forming a design, in the present instance of diamond shape, by 60 applying within one diamond shaped portion of the said surface, as at *b*, red grit or sand to the sticky surface of which it adheres or is embedded, and then to the adjacent section, as at *c*, I may apply a blue grit 65 or sand, and the next section *d* red grit, and the section *e* blue grit, and so on, though I do not limit myself as to the colors, and more than two colors may be used, if desired. I may leave a margin, as at *f*, free from the 70 grit or sand, which forms the underlap for the adjacent section, and which allows the patterns to be matched.

I prefer to use a natural colored rock crushed, as this gives a color that does not 75 fade. My invention produces a very novel article, the crushed rock being embedded in different colors into the asphalt surface, and the result is that the designs are immediately adjacent each other, the differently colored material being directed to the hot asphalt surface through the machine disclosed in the patent referred to, and this machine, while feeding one color, protects the other surface of the sheet so that there is no inter- 80 mingling of colors, and the line of demarcation between the designs is clearly discernible by the colors accentuated by the slight depressions formed by the projecting ribs of 85 the machine in passing over the surface of 90 the body material.

I of course do not limit myself to the diamond shape of design, as this may vary according to the taste or fancy of the manufacturer or the customer.

95 I claim as my invention:—

1. As a new article of manufacture, a composition roofing sheet having an asphalt coating, said coating having partly embedded therein over its surface to be exposed 100 grit of different colors when applied and arranged to form different colored designs, the outer surfaces of the designs being in the same plane, the designs being separated by a fine line, the lines being depressed and only 105 broad enough to separate and sharpen the outline of the designs and the sheet being free of grit on one edge to form an underlap margin.

2. As a new article of manufacture, a com- 110

position roofing sheet having an asphalt coating, said coating having partly embedded therein over its surface to be exposed grit of different colors when applied and arranged to form different colored designs, the outer surfaces of the designs being in the same plane, the designs being separated by a fine line, the lines being depressed and

only broad enough to separate and sharpen the outline of the designs.

In testimony whereof, I affix my signature in presence of two witnesses.

ALEXANDER S. SPIEGEL.
